A. GOTTSCHALK

DOOR CONTROL APPARATUS

Filed April 1, 1921

UNITED STATES PATENT OFFICE.

ALBERT GOTTSCHALK, OF NEW YORK, N. Y., ASSIGNEE TO NATIONAL PNEUMATIC COMPANY, OF NEW YORK, N. Y., A CORPORATION OF WEST VIRGINIA.

DOOR-CONTROL APPARATUS.

Application filed April 1, 1921. Serial No. 457,595.

To all whom it may concern:

Be it known that I, ALBERT GOTTSCHALK, a citizen of the United States, residing at New York, county of Bronx, State of New York, have made a certain new and useful Invention in Door-Control Apparatus, of which the following is a specification.

This invention relates to door control apparatus and especially to such type of apparatus as is employed for moving a door carrying a collapsible shoe wherein, when the shoe is collapsed, due to the same encountering an obstruction, during its closing movement, the door motor is actuated, either to arrest its closing movement or to effect a reversal of its movement. The special purpose of the invention is to provide means for actuating the motor or its valve upon collapsing movement of the shoe, which is simple in structure, economical to manufacture, and highly efficient in operation.

A further object of the invention is to provide a connecting mechanism between the collapsible door shoe and the motor which is extremely sensitive, but, at the same time, is composed of but few parts, requiring little or no attention to maintain the same in efficient sensitive operation.

30 A further object is to provide means of similar nature for preventing the collapsing of the door after it has completed its movement towards closed position.

Further objects of the invention will appear more fully hereinafter.

The invention consists substantially in the construction, combination, location and relative arrangement of parts, all as will be more fully hereinafter set forth, as shown in the accompanying drawing, and finally pointed out in the appended claims.

Referring to the figures:—

Fig. 1 is a view in elevation of a door installation embodying my invention, a part of the door shoe being broken away to disclose the construction therein.

Fig. 2 is an enlarged detailed view showing the top front edge of the door structure showing the shoe covering removed.

50 Fig. 3 is an enlarged detailed view partially in section showing one application of the invention wherein the door structure effects an actuation of the motor controlling

valve, the control valve in this instance being shown in section.

The same part is designated by the same reference numeral wherever it occurs throughout the several views.

Reference numeral 1 designates a door unit construction including a slideable door 2 provided with a collapsible shoe 3 at the front edge thereof. Slidably secured to the rear edge of the door is a door arm 4 which is controlled by a motor 5, which motor in turn is controlled by a control valve 6. While I do not desire to be limited or restricted to any particular type of door motor or the actuating means for controlling the door movements, I have selected one simple and efficient type which is commonly utilized today in the street, elevated and subway systems, wherein the motor 5 is of the differential type, the cylinder of smaller diameter communicating by means of a pipe line 7, to passage 8, of valve 6, whereas the cylinder of larger diameter communicates through pipe line 9 to passage 8 to valve 6, the passage 8 of valve 6 likewise being in communication with a pipe line 10 to fluid pressure supply source. The valve 6 is likewise provided with passages 11 and 12 in communication with each other and a handle 13 for controlling the valve position. Thus it will be seen that when the valve is in the position as shown fluid pressure from the pipe line 10 passes through passage 8 of valve 6 to pipe lines 7 and 9 to the ends of the respective cylinders of the motor 5 with the result that the differential pistons operating within the motor 5 causes the door arm 4 to assume its door closed position as illustrated in the drawing. To open the door the handle 13 of valve 6 is turned clockwise so that passage 11, 12, establishes communication between the exhaust port or pipe 61 and the pipe line 9 while at the same time the passage 8 breaks off communication between the source pipe 10 and the pipe line 9 but maintains communication between source pipe 10 and pipe line 7, as will be readily understood. This movement of the valve, while maintaining fluid pressure behind the piston of smaller diameter in the motor 5, opens the cylinder of larger diameter thereof to exhaust through connection 61 with the result that the motor is therefore actuated, the arm 4

rocked and the door 2 opened. It will therefore be apparent that with this particular type of motor illustrated, to effect the door opening movement of the motor, it is merely necessary to open the cylinder of larger diameter of motor 5 to exhaust and while, as above stated, my invention in its broadest scope is not directed to any particular type of door motor control, I have illustrated my invention of collapsible shoe construction as controlling this type of motor to, upon being collapsed, exhaust the fluid pressure from behind the larger cylinder of motor 5. In accordance with my invention I mount on the front edge of the door one or more ear lugs 15. In the form shown I employ two ear lugs 15, one near the top and one near the bottom of the door. The top lug pivotally supports intermediate its ends a three leg bell crank lever, one leg 16 of which is secured to the front edge of the shoe 3 which, it will be understood, encloses the front edge of the door, the lugs 15, and the levers pivotally carried thereby. Another leg 17 of the bell crank lever has pivotally secured at the end thereof a rod 18, which extends the substantial vertical height of the door for pivotal movement relative thereto through one or more guide plates or collars 19, which guide plates or collars are secured to the door in any suitable manner, for example, screwed thereto. With this construction it will be seen that when the shoe is collapsed, for example, as by meeting an obstruction during the closing movement of the door, the bell crank lever is rocked, with the result that the rod 18 is drawn upwardly. To insure the movement of the rod 18 irrespective of what portion of the door shoe comes in contact with the obstruction, I prefer to pivotally mount a bell crank lever in the bottom lug 15, which bell crank lever is provided with a leg 16, which at one end carries the door shoe and the other end is secured to the rod 18 to similarly, upon collapse of the door shoe at this portion thereof, cause the rod 18 to travel upwardly relatively to the door. By means of this arrangement an extremely sensitive collapsible shoe structure is effected, whereby, at any point throughout the entire height of the door, an obstruction will effect the upward movement of the rod 18, and if the obstruction occurs in the centre of the door, where in practice it is more apt to, and, in fact, does more often occur, both bell crank levers are actuated and operate in unison and in conjunction with each other. To insure the shoe being retained in its normal extended position and to return the same to its normal extended position after the same has been collapsed, as, for example, on meeting an obstruction, I mount one or more springs 20, preferably of the coil type, operating between the guide plates or collars 19,

and similar collars 21, which springs are compressed when the rod 18 is moved upwardly. It is obvious that any other equivalent means may be employed for this purpose but I have found the foregoing, as described, sufficient and efficient. Extending through the bottom of the door and pivotally mounted intermediate its ends on the rear of the door, as shown at 22, is a lever 23, the front end of which is provided with a hole through which the rod 18 extends, the rod 18 being provided with a head 24 at the end thereof to prevent the same from being drawn completely through the hole. The lever 23 extends through a loosely fitting slide collar 25 carried by or secured to what I will term the reverse valve 26 so that the rod may freely pass through the slide collar 25 during the opening and unobstructed closing movements of the door. The slide collar 25 is likewise made sufficiently loose to permit a slight pivotal movement of the lever 23 therein.

The form of reverse valve selected for the purpose of illustration consists of a supply port 30 in communication with any suitable source of supply which allows fluid pressure to enter into a valve controlled passage, which valve is preferably of the puppet type, provided with a stem 31 extending through the top of the reverse valve structure and terminating directly under the lever 23. The valve controls the passage 32, which communicates beneath a plunger 33, which plunger controls a valve 34, which normally closes a passage extending between exhaust port 35 and pipe line 36, which is in communication with the cylinder of larger diameter of motor 5. It will be seen, therefore, that when the valve stem 31 is depressed, fluid pressure is supplied from line 30, through passage 32, under the plunger 33, thereby lifting valve 34 off of its seat and allowing the fluid pressure in the cylinder of larger diameter to escape through the pipe line 36, and exhaust port 35, thereby effecting a reverse movement of the door. Due to the fact that fluid pressure is constantly supplied to the cylinder of smaller diameter of motor 5, it will therefore be seen, that if the motor control valve is in the position shown in Fig. 1 to cause the door to move towards its closed position, if the door meets an obstruction which collapses the shoe 3, the rod 18 will thereby be raised, the lever 23 rocked about its pivotal connection to the door 22 and the valve stem 31 depressed with the ensuing operation hereinafter described.

It is desirable in this type of door operating apparatus to prevent the collapsing of the door shoe when and after the door has become completely closed, to thereby prevent a reversal of the door motor through

deliberate negligence, mischief, or accident when the car is in motion. This may be accomplished in many ways, for example, by properly positioning the reverse valve 26, or 5 by utilizing proper length of lever 23. It will readily be apparent that when the door reaches its closed position the end of the lever 23 may be out of vertical alignment with the valve stem 31, whereby, should the 10 shoe be collapsed and the lever 23 thereby rocked, the reverse valve 26 would not be operated. Therefore, even though the door shoe should be collapsed, the door could not be opened because the door operating arm 15 will have assumed its horizontal position to thereby effect a lock for the door in its closed position in the manner now known in the art. Alternative and additional means may be employed for this purpose, for example, that shown in Figures 1 and 2, whereby the third leg 40 of the bell crank lever 20 comes into contact with a pin 41 carried by the door jamb 42 when the door has reached its completely closed position to thereby prevent even the collapsing of the shoe by 25 preventing any pivotal movement of the bell crank lever relative to its supporting lug 15 and consequently preventing any relative movement between the rod 18 and the 30 door and in consequence any rocking of the lever 23.

Many other modifications and changes 35 may be made in the details without departing from the spirit and scope of my invention as described in the specification and pointed out in the appended claims. Therefore, what I claim as new and useful, and desire to secure by Letters Patent is:—

1. The combination with a door, and an 40 operating motor therefor, of a collapsible shoe supported at the front edge of the door, a slide rod, means on said door on which said rod is pivotally supported intermediate its ends, means for rocking said rod about its 45 pivotal support when said door shoe is collapsed, and a motor control device actuated by said rod when rocked, and means for preventing the actuation of said motor control device after said door has completed its 50 movement towards closed position.

2. The combination with a door, and an operating motor therefor, of a collapsible shoe supported at the front edge of the door, a slide rod, means on said door on which said rod is pivotally supported intermediate its 55 ends, connections between said shoe and said rod whereby said rod is rocked about its pivotal support when said shoe is collapsed, and a motor control device actuated by said rod when rocked, and means for preventing the actuation of said motor control device after said door has completed its movement towards closed position.

3. The combination with a door, and an

operating motor therefor, of a collapsible 65 shoe supported at the front edge of the door, a slide rod pivotally supported intermediate its ends by said door, means for rocking said rod about its pivotal support when said door shoe is collapsed, and a motor control device 70 actuated by said rod when rocked, and means for preventing said shoe from being collapsed after said door has reached its closed position.

4. The combination with a door, and an 75 operating motor therefor, of a collapsible shoe supported at the front edge of the door, a slide rod pivotally supported intermediate its ends by said door, connections between said shoe and said rod whereby said rod is 80 rocked about its pivotal support when said shoe is collapsed, and a motor control device actuated by said rod when rocked, and means for preventing said shoe from being collapsed after said door has reached its closed 85 position.

5. The combination with a door and an operating motor therefor, of a shoe pivotally supported at the front edge of the door, a 90 vertical rod slidably mounted in said shoe, means for moving said rod when said shoe is collapsed, a slide rod, a bracket on said door on which said rod is pivotally supported between its ends, and connected at one end to said vertical rod, and a motor control device 95 actuated by said slide rod when rocked, and means for preventing the actuation of said motor control device after said door has completed its movement towards closed position.

6. The combination with a door and an operating motor therefor, of a shoe pivotally supported at the front edge of the door, a vertical rod slidably mounted in said shoe, means for moving said rod when said shoe is collapsed, a slide rod pivotally supported between its ends by said door, and connected at one end to said vertical rod, and a motor control device actuated by said slide rod 105 when rocked, and means for preventing said shoe from being collapsed after said door has reached its closed position.

7. The combination with a door and an operating motor therefor, of a shoe pivotally supported at the front edge of the door, a vertical rod slidably mounted in said shoe, means for moving said rod when said shoe is collapsed, a slide rod pivotally supported between its ends on said door, and connected at one end to said vertical rod whereby each 115 end of said slide rod is caused to oscillate as the vertical rod moves; a motor control device actuated by the movement of said slide rod, and means for yieldingly retaining said shoe in its extended position.

8. The combination with a door and an operating motor therefor, of a shoe pivotally supported at the front edge of the door, a

vertical rod slidably mounted in said shoe, means for moving said rod when said shoe is collapsed, a slide rod pivotally supported between its ends on said door, by a pivot pin and connected at one end to said vertical rod, and a motor control device actuated by said slide rod when rocked, and means asso-

ciated with said vertical rod for yieldingly opposing any movement thereof relative to said door.

In testimony whereof I have hereunto set my hand on this 30th day of March A. D., 1921.

ALBERT GOTTSCHALK.
